CONFECTIONARY STAND

John H. Heiney, 15989 Woodland Ave., Dearborn, Mich.

Filed Sept. 10, 1962, Ser. No. 71,670

Term of patent 14 years

(Cl. D44—10)

FIG. 1

FIG. 5

FIG. 2

I claim:

The ornamental design for a confectionary stand substantially as shown.
